UNITED STATES PATENT OFFICE.

THOMAS R. GAINES, OF NORWOOD, OHIO.

TAG.

1,392,410.

Specification of Letters Patent.

Patented Oct. 4, 1921.

Application filed November 13, 1917. Serial No. 201,726.

To all whom it may concern:

Be it known that I, THOMAS R. GAINES, a citizen of the United States, residing at Norwood, in the county of Hamilton and 5 State of Ohio, have invented certain new and useful Improvements in Tags, fully described and represented in the following specification and the accompanying drawings, forming a part of the same.

10 This invention relates to marking tags, and more particularly to price tags. The invention has been made with the idea of providing a price tag, the use of which shall prevent or lead to the detection of un- 15 authorized change of the price marking of goods or the sale of goods at less than the marked price. The invention consists in a tag having in addition to the normal visible marking, that is, the price mark and usually 20 a serial number mark in the case of a price tag, a second price and serial number marking, or as it might be, other duplicate marking, which is inaccessible and therefore unalterable without noticeable mutilation of 25 the tag. Such secondary marking will usually be normally concealed as well as inaccessible, and the tag is most desirably provided with a detachable secondary sheet or tag member to bear such duplicate marking 30 which is gummed on one side so that when detached from the tag it may be readily affixed to, for example, a sales slip which goes to the cashier. The invention includes various features of construction and ar- 35 rangements of parts, all as hereinafter described and pointed out in the claims.

The accompanying drawings show a price tag which embodies the features of the invention in the form which I now consider 40 best. In said drawings:-

Figure 1 is a view in front elevation of the tag with a portion of the front sheet of the main tag member removed to show the secondary tag member;

45 Fig. 2 is a cross-sectional view taken on line 2-2 of Fig. 1;

Fig. 3 is a view in front elevation of the tag before the front and back sheets thereof have been secured together to render the 50 secondary tag member inaccessible; and

Fig. 4 is a similar view of the tag in the condition shown in Fig. 3 but with the front sheet removed and showing also a multiple section secondary tag member.

55 Referring to the drawings, the price tag illustrated comprises a main tag member

formed of front and back sheets 1 and 2 respectively, and a detachable secondary tag member or sheet 3 located between and normally hidden by and rendered inaccessible 60 by the sheets 1 and 2. The sheets 1 and 2 of the main tag member may be made of heavy paper or cardboard or other suitable sheet material and are secured together at opposite edges by means which should be 65 permanent for all practical purposes. Most desirably the sheets are secured together by paste at the top edge and by an eyelet 4 which serves to receive a string by which the tag may be fastened to the article to which it 70 belongs. Paste and eyelets 5 or other suitable fasteners may also be used for securing together the opposite or bottom pages of the sheets, or paste alone or mechanical fastening means alone might be used. In 75 order to permit the tag to be opened to give access to and for removal of the secondary tag number 3 without danger of mutilating the secondary tag member or the markings on the main tag member, the front and back 80 sheets are perforated or otherwise weakened on corresponding lines near the bottom as indicated by the dotted lines 7 and 8.

The secondary tag member 3 is formed by a sheet of paper or other suitable material 85 pasted or otherwise secured at one end to one of the sheets of the main tag member with the main portion thereof free from the sheets 1 and 2 so that it may be readily removed therefrom when the main tag mem- 90 ber has been opened, and is desirably made smaller than the sheets 1 and 2 and is positioned with its free edges lying inward away from the edges of the sheets 1 and 2. This sheet 3 is gummed, that is, provided with a 95 coating of suitable adhesive, on one side so that the main portion thereof, which forms the detachable tag member, may, when detached from the tag, serve as an adhesive stamp which may be readily affixed to a sales 100 slip or other article; and for convenience in detaching such stamp the sheet 3 is weakened as indicated by the dotted line 9 in Figs. 1 and 4, on a line above the markings on the sheet.

105 Indicating markings are applied to the outer surface of one of the sheets 1, 2, and also to the ungummed side of the stamp or detachable secondary tag member 3. In the case of a price tag, the marking which appears on both members will usually be the price and in addition thereto a serial num-

ber. On tags for other purposes other suitable indicating markings will be applied in duplicate. As shown, sheet 1 of the main tag member is marked with a serial number 5 and the price of the article to which the tag is to be attached, and the removable or stamp portion of the secondary tag member sheet is marked with the same serial number and the same price.

10 Tags marked with standard numbers and price marks may be made up complete and ready for use with the same serial numbers and price marks or other markings printed or otherwise marked on both the main tag 15 member and the secondary tag member, and with the front and back sheets of the main tag member permanently fastened together at both ends in the form of tag shown to render the secondary tag member inaccessible, or in case of tags of other form embodying features of the invention, otherwise sealed or completed to render the secondary marking inaccessible. Where it is desired to have tags marked as used, the tags of the 20 form shown may be completed except for the sealing of the front and back sheets of the main tag member at one end, such end to be closed and fastened after the desired marking has been placed on both the main 25 and secondary tag members.

When a tag such as shown is attached in its completed form to an article, it will be impossible to change the marking on the secondary tag member without mutilating the 35 main tag member, and the secondary marking will always serve, therefore, as a check on the main marking. While price tags embodying the invention might be made use of in various ways, the plan which I recommend is that when a sale is made the sales 40 clerk is to open the tag by tearing off the lower end on the perforated lines and remove the secondary tag member or stamp 3 and, when there is only a single stamp 3, 45 affix the same to the sales slip which is sent with the purchase money to the cashier. The cashier on receiving the sales slip will check the amount entered on the sales slip with the price appearing on the tag stamp 50 and thereby be advised whether or not the article has been sold at the proper price. The mere fact of having to follow this practice will deter the sales clerk from selling goods at any price other than the marked 55 price; and if on opening a tag the sales clerk should find that the price on the secondary tag member does not agree with the main marking he will know that an unauthorized change has been made in the 60 main marking on the check and will be governed accordingly in calling the matter to the attention of the proper authority, or otherwise acting according to instructions.

The secondary tag member is shown in 65 Fig. 1 as providing only one detachable

stamp, but it is sometimes desirable to have two or more such stamps or detachable secondary tag members. An arrangement providing two such members is illustrated by Fig. 4, which shows the device as having two 70 detachable stamps 3^a provided by a single inserted sheet which is perforated or otherwise weakened on two lines 9^a, each such stamp or position 3^a being marked, as shown, 75 with the price and serial number which appears on the main tag member. In using a tag having a plurality of detachable tag members or stamps, one of the stamps when removed from the opened tag may be placed on the sales slip which goes to the cashier 80 and one on the customer's sales slip which goes to the wrapper, and the stamps may thus take the place of the customary pencil marking of the sales slips. Additional insurance against fraud is thus afforded. The 85 two or more stamps 3^a of each tag may be of different colors.

What is claimed is:

1. A marking tag comprising front and back sheets secured together to prevent access to the space between the sheets, and a detachable sheet secured in the space between said front and back sheets and inaccessible except by mutilation of the tag. 90

2. A marking tag comprising a main tag member formed of front and back sheets, and a detachable secondary tag member formed of a sheet secured between the sheets of the main tag member and bearing markings corresponding to markings on the main tag member, the front and back sheets of the main tag member being secured together at opposite portions thereof to prevent access to the secondary tag member without mutilation of the main tag member. 100

3. A marking tag comprising a main tag member formed of front and back sheets and a detachable secondary tag member formed of a sheet smaller than the main tag member secured between the sheets of the main tag member, the front and back sheets of the main tag member being secured together at opposite edges thereof to normally prevent access to the secondary tag member, and said front and back sheets being weakened along a line outside the periphery of the secondary tag member to facilitate separation thereof to give access to the secondary tag member without mutilation of the secondary tag member. 110

4. A marking tag comprising a main tag member having front and back sheets, and a detachable secondary tag member formed of a sheet secured between the sheets of the main tag member and bearing markings corresponding to markings on the main tag member; the front and back sheets of the main tag member being secured together to normally prevent access to the secondary tag member, and the sheet forming the sec- 120 125

ondary tag member being weakened to permit ready detachment of the marked portion thereof without mutilation thereof.

5. A marking tag, comprising a main tag member formed of front and back sheets, and a secondary tag member formed by a gummed sheet bearing markings corresponding to markings on the main tag member, the secondary tag member being held between the sheets of the main tag member to be inaccessible without mutilation of the

main tag member when the front and back sheets thereof are secured together, and being removable from the main tag member when the latter is opened.

15 In testimony whereof I have hereunto set my hand in the presence of two subscribing witnesses.

THOMAS R. GAINES.
